UNITED STATES PATENT OFFICE.

VINCENT G. APPLE, OF DAYTON, OHIO.

DESIGN FOR A VEHICLE-LAMP.

41,611.

Specification for Design.

Patented July 25, 1911.

Application filed May 31, 1911. Serial No. 630,486. Term of patent 14 years.

To all whom it may concern:

Be it known that I, VINCENT G. APPLE, a citizen of the United States, residing at Dayton, in the county of Montgomery and State of Ohio, have invented a new, original, and ornamental Design for Vehicle-Lamps, of which the following is a specification, reference being had to the accompanying drawings, forming a part thereof.

In the drawing, wherein I have shown my

new design, Figure 1 is a top elevation; and Fig. 2 is a front elevation thereof.

I claim:

The ornamental design for a vehicle lamp, as shown.

VINCENT G. APPLE.
